SUPPORT FOR DRILLING MACHINES

Archibald R. Lawrence, Montreal, Quebec,
Canada

Application January 21, 1933, Serial No. 652,885

20 Claims. (Cl. 255—51)

This invention relates to supports or supporting mechanism for drilling machines such as are used in mines for loosening ore, coal or other material from the formation in which it is found, or for the purpose of drilling holes in the formation to facilitate the employment of explosives in loosening the material.

Such drilling machines must be firmly supported while in operation to permit them to drill effectively. It is customary to support them either on a vertical column or upon a cross arm attached to the column. The column is set up in proximity to the formation to be drilled, and the drill is moved from time to time up or down the column in order to reach as much of the material as possible without moving the column. When a cross arm is used, it is adjusted up or down the column and the drilling machine is adjusted to different positions along the cross arm so as to increase the radius of operations.

In order to secure the cross arm in position at any given elevation on the column, it is necessary to "set up" a number of large nuts on bolts arranged to clamp the cross arm to the column. Similar bolts and nuts are also arranged to clamp the drilling machine to the cross arm, and an especially long wrench is used for tightening and loosening these nuts. To change the angular position of the drilling machine, a clamp is provided which grips the conical base of the drill carriage, this clamp being held tight by means of a king bolt and nut. The amount of labor involved in shifting the position of the drill is very considerable as it requires great physical strength to both loosen and tighten the nuts. The general practice is to have a second operator or helper whose only work consists of the drudgery of handling the wrench. Even when the bolts are set up as tightly as possible by hand, however, it not infrequently happens that the clamping is insufficient to prevent the drilling machine from moving out of place during its operation.

It is the aim of the present invention to provide a drilling machine support from which are eliminated clamping devices involving the use of bolts and nuts and hand manipulated wrenches.

It is the aim of the invention also to provide an improved clamping mechanism by means of which the drilling machine may be more quickly and easily shifted either upon the arm or the column, or the arm shifted upon the column, and which at the same time will hold the drill securely in any position to which it is moved, and to provide a mechanism of sturdy construction which

will withstand the rough usage to which it must necessarily be subjected.

Another object of the invention is to provide a supporting mechanism which is adapted to support drilling machines of standard construction so that it is unnecessary to modify these machines in order that they may be used upon the supporting mechanism.

A further object of the invention is to provide supporting mechanism in which by means of a single manipulation the drilling machine may be released for shifting angularly as well as bodily, and likewise reclamped in its new position.

It is another object of the invention to provide a supporting mechanism which is capable of producing ample clamping pressure between the various parts without rendering the apparatus cumbersome and difficult to handle, and also without restricting the range of drilling of the drilling machine.

The invention will be understood from a consideration of the following detailed description of two embodiments of the invention as illustrated in the accompanying drawings. In these drawings:

Fig. 1 represents a view in elevation of my improved drilling machine supporting mechanism;

Fig. 2 represents a view in elevation looking at the end of the supporting arm shown in Fig. 1 and including only a portion of the column;

Fig. 3 represents a cross-sectional view taken on the plane indicated by the line 3—3 of Fig. 1 to show the construction of the holding device by means of which the drill is mounted on the supporting arm;

Fig. 4 represents a top plan view of the holding device shown in Fig. 3;

Fig. 5 represents a cross-sectional view taken on the horizontal plane indicated by line 5—5 of Fig. 1;

Fig. 6 represents a cross-sectional view taken on the vertical plane indicated by the line 6—6 of Fig. 5;

Fig. 7 represents a cross-sectional view taken on the vertical plane indicated by line 7—7 of Fig. 5;

Fig. 8 represents an enlarged cross-sectional view taken on a vertical plane indicated by the line 8—8 of Fig. 6, through the valve mechanism.

Figs. 9 and 10 represent enlarged vertical sections taken longitudinally through the respective members of the valve;

Fig. 11 represents a perspective view of certain of the actuating parts;

Fig. 12 represents a fragmentary cross-sec-

tional view similar to Fig. 5 illustrating a modified form of mechanism;

Fig. 13 represents a cross-sectional view taken on a vertical plane indicated by the line 13—13 of Fig. 12;

Fig. 14 represents a cross-sectional view taken on a vertical plane indicated by line 14—14 of Fig. 13;

Fig. 15 represents an enlarged cross-sectional view of one of the parts shown in Figs. 12 and 13; and

Figs. 16 to 19, inclusive, are views representing two modified forms of one of the parts of the apparatus.

15 Referring now to the accompanying drawings, the invention is illustrated in connection with a vertical supporting column 1 used in underground work and adapted to be fixed in position by means of a plate 2 which bears against a beam or other available object at the ceiling and by means of a jack 3 at the bottom which rests on the floor of the mine. A horizontal arm 4 extends to the right of column 1 and carries the drilling machine 5 which is attached to this arm 25 by a holding device 6. Arm 4 has a bracket 7 which surrounds column 1. In accordance with my invention bracket 7 is held in any given position upon column 1 by means of radially movable engaging elements or segments 8 which are 30 provided with means, to be described, for moving them inwardly to disengage them from the base 7 and outwardly to engage them therewith with sufficient pressure to hold the arm 4 in place.

35 Similarly arm 4 is provided with radially movable segments 9 which can be engaged and disengaged from the lower portion of holding device 6, this device being so constructed that the movement of the segments 9 actuates the members of holding device 6 to cause them to clamp and hold the base or cradle of the drilling machine 5, as will presently be described in greater detail. The movement of the segments 8 and 9 both to their clamping and to their release positions is accomplished by fluid pressure, utilizing whatever medium is available in the particular mine, whether air or water.

The movement of the segments 8 of the column is controlled by means of a valve mechanism indicated generally at 10 and provided with an operating handle 11, the pressure fluid being supplied through a hose connection 12. The segments 9 on the arm 4 are controlled by means of a separate valve indicated generally at 13 having an operating handle 14 and supplied with pressure fluid through the hose connection 15.

60 The column 1 and the arm 4 may conveniently be made of piping in accordance with the usual practice. The rectangular segments 8 and 9 project through rectangular slots cut in the piping. The segments are arranged in slightly spaced relation throughout the entire length of the column and of the arm, so that the arm may be supported close to the ground or close to the ceiling or in any intermediate position and so that the drilling machine may be placed at any point throughout the length of the arm. It will be understood that the holding device 6 and the bracket 7 may be placed each over a single segment as shown in Fig. 1, or they may be arranged so as to bridge the gap between two adjacent segments so that the clamping pressure will be exerted by two segments instead of one. The width of bracket 7 and of holding device 6, 75 however, is preferably such that it is impossible

for either of them to be engaged by three adjacent segments.

Preferably, the segments 8 and 9 are arranged in pairs, that is, there are two similar segments on diametrically opposite sides of the center line of the column and arm as shown in Fig. 3. If desired, however, only a single row of segments may be used. Also, such row may be placed along the bottom or top of the arm 4 instead of along the side of the arm. When the segments are retracted they are substantially flush with the surface of the cylindrical arm and column (as shown in Fig. 7), and when they are moved outwardly to clamping position they extend beyond the surface of the column (as shown in Figs. 2 and 3 and certain of the other figures of the drawings).

The holding device 6 comprises a pair of upright jaws 16 and 17 held in approximately parallel pivoting relation by means of an H-bolt 18. 20 All three of these members can conveniently be made of cast steel and have ample cross-sectional area at all points to withstand the comparatively large stresses which are set up in them when the drilling machine is held in clamped 25 position.

The lower portions of jaws 16 and 17 are substantially semicircular in shape so as to nearly surround the arm 4. The curvature of their inner surfaces substantially fits the curvature of segments 9 so that the pressure will be uniform throughout the area of contact. The upper portions of jaws 16 and 17 are provided with co-acting semi-circular dove-tailed formations 19 and 20 which grasp a standard conical base 21 35 projecting downwardly from the cradle of the drilling machine 5.

The H-bolt 18 which connects the jaws 16 and 17 is received within recesses 22 and 23 in the respective jaws. The downwardly extending portions of these recesses permit the entrance of the two heads of the H-bolt, and the horizontal portions are flared slightly as indicated so as to permit the necessary pivotal movement of the jaws with respect to the H-bolt.

It will be understood that when the segments 9 are extended to the position shown in Figs. 1, 2 and 3, the lower portions of the jaws 16 and 17 are thereby forced apart, while the upper portions are forced towards one another, clamping the 50 dove-tailed formations 19 and 20 firmly against the conical base 21 of the drill. When, however, the segments 9 are retracted, the lower portions of jaws 16 and 17 are loosened from these segments and the dove-tailed formations 19 and 20 release 55 their pressure upon conical base 21, the pressure upon all of these parts being eased to a sufficient extent so that the drill 5 may be swung about the conical base 21 as a pivot to change its angular position and the holding device 6 may be slid 60 bodily along the arm 4 to move the drill to a different position on the arm.

The mechanism for effecting the radial movement of segments 8 and 9 is illustrated more particularly in Figs. 5, 6 and 11 of the accompanying drawings. Mounted at the center of arm 4 and extending substantially throughout its length there is a cam actuating rod 24 upon which are fixed at spaced points along the same, double opposed cams 25 and 26, there being one of each 70 of such cams for each pair of segments 9. Segments 9 are provided at each end with inwardly projecting legs 27 and 28 upon the ends of which are cam surfaces 29 and 30 which coact with the cams 25 and 26. Hence, as actuating rod 24 is 75

5 moved to the right, segments 9 will be forced outwardly. Cams 25 and 26 and cam surfaces 29 and 30 are moreover provided with interengaging surfaces such, for example, as the dove-tailed connections 31 shown in Figs. 11, 3 and 7. Therefore, when actuating rod 24 is moved to the left, segments 9 will be positively retracted.

10 Actuating rod 24 is moved by means of a plurality of pistons 32 mounted in spaced relation on the actuating rod, and surrounded by cooperating cylinders 33. These pistons and cylinders are placed respectively between each diametrically opposed pair of segments 9, the space between the feet 27 and 28 on the segments being utilized 15 for the reception of these cylinders. Each of these cylinders is provided at each end with stuffing boxes 34 and 35, as indicated in Fig. 5 to prevent the escape of the operating fluid.

20 In order to hold the cylinders 33 in fixed position with respect to the hollow arm 4, they are provided on their opposite sides with bosses 36 (Fig. 3) which project outwardly into contact with the interior wall of arm 4. These bosses are tapped in their outer surfaces to receive holding 25 screws 37 which are inserted from the exterior of the arm.

25 It will be understood that fluid pressure is admitted simultaneously to corresponding ends of all of the cylinders 33, and inasmuch as the holding device 6 of the drill 5 is usually placed over a single pair of segments 9, the pressure upon all of the pistons 32 is exerted on a single pair of segments. Therefore, sufficient clamping pressure is obtained with cylinders of comparatively small 35 diameter which can be received within the drilling arms of standard size, and utilizing an air pressure, for example, of 75 to 85 pounds per square inch as is usually employed in mines for the operation of the drilling machines.

40 Cams 26 and their coacting feet 28 are made longer than cams 25 and feet 27 in order to reduce the length of the central unsupported portions of the segments 9. In fact, the space between the feet 27 and 28 will be made only sufficient to accommodate the air cylinders 33 and allow clearance 45 to facilitate the assembly of the parts.

45 To convey fluid under pressure to the several cylinders 33, ducts or conduits 38 and 39 extend longitudinally of arm 4, as may be seen in Fig. 6, 50 and these may be placed respectively below and above the cylinders. Connections 40 place duct 38 in communication with the left-hand ends of each of cylinders 33, and connections 41 serve a similar purpose with respect to duct 39 and the 55 right-hand ends of the cylinders.

50 The control valve 13 may be placed at either the inner or the outer end of arm 4, and for convenience it is shown in the drawings at the outer end. In practice the control valve will be placed 60 at the inner end of arm 4 adjacent base 7, the valve handle projecting through a slot in the arm. This affords greater protection to the valve against damage in handling the supporting mechanism, and simplifies the lubrication of the operating mechanism which will be described below.

65 Valve 13 is illustrated in detail in Figs. 8, 9 and 10. The stationary member 42 of this valve is shown in detail in Fig. 9 and the movable member 43 in Fig. 10. Stationary member 42 is a cylindrical body which is received within the end of arm 4 which is machined so as to provide a shoulder and packing ring 42' to prevent the passage or air. The member is held in position by means of screws 44. Member 42 has a conical 70 valve surface 45 with which a complementary

conical surface 46 on rotatable valve member 43 coacts.

Rotatable member 43 is provided with two inlet ports 47 and 48 which extend through the member parallel with its operating shaft 49 upon 5 which it is mounted. A side view of one of these ports is shown in Fig. 10, and an end view of each of the ports is shown in Fig. 8, which also shows their angular relationship. Rotatable member 43 also has two exhaust slots 50 and 51 10 in its conical surface. A side view of one of these slots is shown in Fig. 10, and the outline representing the end view of each of these slots is shown in dotted lines in Fig. 8. This view also shows their angular relationship. 15

In stationary valve member 42 there are two through ports 52 and 53 extending from the conical valve surface 45 through the valve member and communicating respectively with ducts 38 and 39. Member 42 also has a central air 20 passage 54 at the apex of its conical valve surface 45.

In Fig. 6 the handle 14 of the valve has been turned to the position for causing the segments 9 to be moved outwardly to clamping or engaging 25 position, and the pistons 33 are shown as having been moved to this position both in Fig. 6 and Fig. 5. The air enters from the hose connection 15 which admits it into a V-shaped circular passage 55 in the outer surface of rotatable valve 30 member 43 which is in communication with both of ports 47 and 48. As port 47 is opposite port 52 in stationary valve member 42, the air is conveyed to port 47 and thence through port 52 into duct 38 and through connections 40 to the left-35 hand ends of each of the cylinders 43, thus moving pistons 33 to the positions indicated.

In order to allow the escape of air from the right-hand ends of cylinders 33 during this movement of the pistons, exhaust slot 51 is in 40 alignment with port 53, thus allowing the air from duct 39 to pass through port 53 in the exhaust slot 51 and thence as shown by the arrows in Fig. 6 into air passage 54 at the center of stationary valve member 42 and thence into the interior of arm 4 from which it escapes to the atmosphere through an aperture 56. 45

It will be understood that when valve member 43 is shifted counterclockwise, as viewed in Fig. 8, inlet port 48 will be brought over port 53 50 of stationary valve member 42. This will also bring exhaust slot 50 opposite port 52, and in this position of the valve, just the reverse operation will take place, that is, the left-hand sides of cylinders 33 will be connected to atmosphere, 55 and the air pressure from hose connection 15 will be admitted to the right-hand sides, thereby moving actuating shaft 24 to the left and reTRACTING the segments 9.

If valve handle 14 is shifted in the opposite direction, i. e., to rotate valve member 43 clockwise, as viewed in Fig. 8, all ports will be flanked with the segments in clamped position. This is important in case of failure of the air supply.

The mechanism for actuating the segments 8 65 of column 1 is the same as that which has just been described for actuating the segments 9 of the arm 4, and it is thought necessary to refer only briefly to this mechanism. The actuating rod is shown at 57 in Figs. 5 and 6, and two of 70 the operating cylinders are indicated at 58, one of these being shown in dotted lines in Fig. 1. Air ducts 59 and 60 communicate with control valve 10 located at the bottom of column 1 as previously mentioned. This valve is of similar 75.

construction to valve 13 except for the fact that its operating handle 11 projects through a slot 61 in one side of the column.

The segments 8 are actuated by double opposed cams 62 and 63, and these segments are thereby forced outwardly into frictional engagement with the interior surfaces of the hollow cylindrical bracket 7 which forms a solid massive ring surrounding column 1.

10. Arm 4 is secured in any appropriate way to this bracket, and as shown in the drawings bracket 7 is provided with a threaded extension 64, the end of the arm being screwed on to this extension. The arm and bracket may also be welded together, or the bracket may be in the form of a two-part clamp bolted together as in the present practice.

In order to lubricate the several cam surfaces, actuating rod 24 is drilled longitudinally, as shown in Fig. 5 at 76, and branch passageways lead from this central passageway to each of the surfaces of the double opposed cams 25 and 26 as indicated. When actuating member 24 is moved to its opposite position from that shown in Fig. 5, a cross passageway 77 which communicates with passageway 76 is brought into alignment with a passageway 78 into the outer end of which a lubricant connection 79 is tapped. To this a lubricant gun supplying semi-solid lubricant under pressure may be attached.

30. With this arrangement all of the friction surfaces can be lubricated simultaneously and very quickly, and at the same time it is impossible to lubricate them without moving them to release position where there will be no pressure between the surfaces, thus insuring that they will all receive lubrication.

With valve 13 located at the inner end of arm 4, as above mentioned, cross passageways 77 and 78 can be eliminated, and passageway 76 continued to the right-hand end of actuating shaft 24. The lubricant connection 79 can then be tapped directly into passageway 76 as will be understood.

45. In Figs. 12 to 15, inclusive, there is illustrated a modified form of mechanism for communicating the motion of the actuating rod to the expandable segments. The segments 65 are actuated by rod 66 upon which a plurality of pistons 67 are mounted, these pistons having cylinders 68. As before, one cylinder is provided for each pair of segments, but the cylinders are placed intermediate the segments so that there is a greater spacing between segments. Actuating rod 66 is provided opposite each pair of segments with a set of rack teeth 69 which coact with pinion teeth 70 mounted at the center of an elongated double nut member 71. The end portions of double nut member 71 are threaded in opposite directions and correspondingly threaded stems 72 and 73 are fixed to the segments 65. Hence, the movement of rod 66 in one direction by cylinder 68 causes the rotation of the double nut member 71 and thus forces outwardly the stems 72 and 73 and the segments 65. The opposite movement of actuating rod 66 causes the positive retraction of the segments.

70. Each segment is provided with two threaded stems 72 or 73 so that it is supported at each end against clamping pressure. Moreover, each stem 72 on one side of the drill supporting arm or column is in axial alignment with the double nut 71 and with the opposite threaded stem 73 so that the clamping stress of the segments is borne entirely by the stems 72 and 73 and the double

75. threaded nut 71, and all such stress is removed from actuating rod 66.

With this construction the actuating rod 66 is not mounted concentrically with the supporting arm or column as before, and the cylinders 68 may be mounted directly upon the interior wall of the arm or column as indicated in Fig. 14. The air ducts 74 and 75 are both situated on the same side of the cylinders 68.

It will be understood that this modified actuating mechanism may be used for moving the clamping segments of either the cross arm 4 or the column 1, or both, and that controlling valves will be provided as previously described.

10. Referring now to Figs. 16 and 17, there is here 15 illustrated a modified form of the holding device 6. Instead of being held together by the H-bolt, its jaw members 80 and 81 are connected by means of a king bolt 82 made in two separate halves 83 and 84 which are connected together by a pivot 20 pin 85 so as to allow the clamping movement of the jaw members to take place. It will be understood that the lower jaws of this modified holding device engage the arm 4 while the upper jaws engage the conical base 21 of the drill 5. 25

The right-hand half of the king bolt is held in position in its aperture in jaw member 81 by means of a nut 86 which is set up tight after the assembly of these two parts, this half of the king bolt being fixed permanently in position. The 30 other half 83 of the king bolt is threaded at its outer end to receive an elongated sleeve 87 which is intended to be turned by hand without the use of a wrench. It may be knurled or otherwise roughened to provide a good gripping surface for 35 the hand.

In use, the slack or clearance between the upper jaws and conical base 21 and between the lower jaws and expanding segments 9 is taken up by turning the sleeve 87. Then fluid pressure 40 valve 13 is opened to cause segments 9 to expand and clamp the drilling machine in place. With this form of holding device, the threaded sleeve and bolt permits of a fine adjustment by hand of the tightness of the device when the drilling machine is "loose", or, in other words, unclamped. The operator will soon learn just the adjustment of this sleeve to give him freedom to swing his machine and just the tightness to keep the machine from flopping over. Moreover, by 45 taking up the clearance by means of the threaded sleeve 87, the necessary outward movement of segments 9 can be reduced for the same length of travel of the actuating rod 24 and hence the angle of the wedging cams 25 and 26 can be made less 50 steep, thus producing greater pressure against the movable segments 9 and increasing the clamping pressure of the apparatus. 55

In Figs. 18 and 19 there is shown a further modification of holding device 6. This form of 60 holding device is like that just described in connection with Figs. 16 and 17 except for the construction of the king pin. As shown in Fig. 18, the two halves of king pin 88 are connected together by interlocking or coupling heads 89 and 65 90. These heads are hooked together as shown in Fig. 18 and held in this position by the walls of apertures 91 and 92. These interlocking heads may have considerable width as shown in Fig. 19, and afford a connection between the two 70 halves of the king pin which possesses somewhat greater strength than the pivoting pin connection shown in Figs. 16 and 17. The slight pivotal movement necessary between the two halves of king pin 88, in order to permit the necessary 75

motion of the clamping members, is provided for through the curvature of the heads 89 and 90 and the allowance of a slight clearance between the various parts, that is, between the two heads themselves and also between the heads and the walls of apertures 91 and 92.

By means of the present invention much of the drudgery attendant upon the moving of a rock drill from one position to another is eliminated, the change may be made in much less time than formerly required, and the drill is securely held in position so that the annoyance of having the drill shift its position during operation is avoided. This positive holding of the drill in any desired position is obtained because of the fact that the clamping pressures which are produced by the segment operating mechanism which I have provided are greater than can be obtained with the use of clamping bolts and nuts, even when the wrench for setting up these parts is manipulated by a man of unusual strength.

It will be understood that the foregoing are exemplifying disclosures of the apparatus of my invention and that changes may be made in the construction of the supporting mechanism and still retain the gist or spirit of my invention. The scope of the invention is set forth in the appended claims.

30 I claim:

1. A supporting mechanism for drilling machines comprising the combination of a supporting member, a drilling machine, a holding device for the drilling machine on said supporting member, securing means on said supporting member to engage said holding device, and clamping means on said holding device actuated by the securing means on said supporting member for holding the drilling machine in position.

40 2. A supporting mechanism for drilling machines comprising the combination of a supporting member, a drilling machine, a holding device having pivoted clamping means coacting with the drilling machine and with said supporting member to mount the drilling machine thereon, engaging elements on said supporting member for expanding one end of said holding device and simultaneously contracting the opposite end thereof, thereby securing said holding device to said supporting member and said drilling machine to said supporting device, and means for actuating said engaging elements.

45 3. A supporting mechanism for drilling machines comprising the combination of a supporting member, a drilling machine, a holding device adjustably mounted on said supporting member, securing means associated with said supporting member for engaging the holding device in adjusted position thereon, fluid pressure means for actuating said securing means, and clamping means on said holding device actuated by the securing means associated with said supporting member for holding the drilling machine in position.

50 4. A supporting mechanism for drilling machines comprising the combination of a supporting member, a securing element on said supporting member, a drilling machine support carried by said supporting member and fixed in position on said supporting member through the action of said securing element, actuating means within said supporting member for actuating said element, and connections between said element and said actuating means for causing the

5 element to be moved to securing position.

5 5. A supporting mechanism for drilling machines comprising the combination of a hollow cylindrical supporting member, a pair of oppositely disposed clamping segments projecting through apertures in said supporting member, wedging means disposed between said clamping segments for forcing said segments apart and causing their surfaces to extend beyond the surfaces of said supporting member, means within said supporting member for actuating said wedging means, and interlocking sliding connections between the said wedging means and the clamping elements so as to positively move said elements both into and out of clamping position.

10 6. A supporting mechanism for drilling machines comprising the combination of a hollow cylindrical supporting member, a pair of oppositely disposed clamping segments projecting through apertures in said supporting member, a fluid pressure cylinder mounted between the oppositely disposed clamping segments, a piston in said cylinder having a piston rod connected therewith and projecting through both ends of the cylinder, wedging means mounted upon each 15 end of said piston rod, and feet at each end of said segments extending towards said wedging means and having cam surfaces coacting therewith for forcing said segments to clamping position.

20 7. A supporting mechanism for drilling machines comprising the combination of a hollow cylindrical supporting member, a pair of oppositely disposed clamping segments projecting through apertures in said supporting member, a 25 double opposed oppositely threaded nut, a threaded stem on each of said segments engaging one of the threads of said nut, and means for rotating said nut to operate said clamping segments into and out of clamping position.

30 8. A supporting mechanism for drilling machines comprising the combination of a hollow cylindrical supporting member having throughout its length spaced apertures arranged in pairs diametrically opposite one another, oppositely 35 placed pairs of clamping segments in said apertures, double opposed nuts for actuating said clamping segments, an actuating rod arranged to rotate all of said nuts simultaneously, and a plurality of coacting pistons and cylinders for moving the actuating rod.

40 9. A supporting mechanism for drilling machines comprising the combination of a supporting member, a drilling machine, a holding device for the drilling machine on said supporting member, a pair of oppositely disposed segments projecting through apertures in said supporting member, double opposed actuating means between the opposed segments for forcing said segments apart and causing their surfaces to extend beyond the surfaces of said supporting member to engage said holding device, means within said supporting member for actuating said wedging means, and clamping means on said holding device actuated by the said segments for holding the drilling machine in position.

45 10. A supporting mechanism for drilling machines comprising the combination of a supporting member, a drilling machine, a holding device for the drilling machine on said supporting member, a pair of oppositely disposed segments projecting through apertures in said supporting member, wedging means disposed between said segments for forcing said segments apart and causing their surfaces to extend beyond the sur-

faces of said supporting member to engage said holding device, means within said member for actuating said wedging means, and clamping means on said holding device actuated by said segments and holding the drilling machine in position.

11. A supporting mechanism for drilling machines comprising the combination of a supporting member, a drilling machine, a holding device for the drilling machine on said supporting member, a pair of oppositely disposed segments projecting through apertures in said supporting member, wedging means disposed between said segments for forcing said segments apart and causing their surfaces to extend beyond the surfaces of said supporting member to engage said holding device, a fluid pressure cylinder mounted between said segments for actuating said wedging means, and clamping means on said holding device actuated by said segments for holding the drilling machine in position.

12. A supporting mechanism for drilling machines comprising the combination of a hollow cylindrical supporting member, a drilling machine, a holding device for the drilling machine on said supporting member, said member having a plurality of apertures arranged in spaced relation throughout the length thereof, a segment mounted to reciprocate radially in each of said apertures, actuating means for each of said segments for reciprocating the same to cause them to engage said holding device, a power device for operating each of said actuating means, means interconnecting said power devices so as to transmit the work done by said devices to each of said segments, and means on said holding device actuated by said segments for holding the drilling machine in position.

13. A supporting mechanism for drilling machines comprising the combination of a hollow cylindrical supporting member, a drilling machine, a holding device for the drilling machine on said supporting member, said member having a plurality of apertures arranged in spaced relation throughout the length thereof, a segment mounted to reciprocate radially in each of said apertures, actuating means for each of said segments for reciprocating the same to cause them to engage said holding device, a fluid pressure cylinder having a piston therein for operating each of said actuating devices, means interconnecting the pistons of said cylinders so as to transmit the combined pressure from said pistons to each of said segments, and clamping means on said holding device actuated by said segments for holding the drilling machine in position.

14. A supporting mechanism for drilling machines comprising the combination of a hollow cylindrical supporting member, a drilling machine, a holding device for the drilling machine on said supporting member, said member having throughout its length spaced apertures arranged in pairs diametrically opposite one another, oppositely placed pairs of segments in said apertures, an actuating rod extending longitudinally within said supporting member having double opposed cams for actuating said segments to engage said holding device, said cams being mounted in spaced relation thereon between each of said pairs of segments, means for shifting said rod longitudinally to move said segments to clamping position, and clamping means on said holding device actuated by said segments for holding the drilling machine in position.

15. A supporting mechanism for drilling machines comprising the combination of a hollow cylindrical supporting member, a drilling machine, a holding device for the drilling machine on said supporting member, said member having throughout its length spaced apertures arranged in pairs diametrically opposite one another, oppositely placed pairs of segments in said apertures, an actuating rod extending longitudinally within said supporting member having double opposed cams for actuating said segments to engage said holding device, said cams being mounted in spaced relation thereon between each of said pairs of segments, a plurality of pistons mounted on the actuating rod, cylinders cooperating with said pistons, means for controlling a supply of pressure fluid to said cylinders to cause said engaging segments to be moved to engaging position, and clamping means on said holding device actuated by said segments for holding the drilling machine in position.

16. A supporting mechanism for drilling machines comprising the combination of a hollow cylindrical supporting member, a drilling machine, a holding device for the drilling machine on said supporting member, a securing element movable in an aperture in the side of said supporting member to engage said holding device, actuating means for forcing said member outwardly, fluid pressure means within said hollow supporting member for operating said actuating means, and clamping means on said holding device actuated by said element for holding the drilling machine in position.

17. A supporting mechanism for drilling machines comprising the combination of a hollow cylindrical supporting member, a drilling machine, a holding device for the drilling machine on said supporting member, a securing element movable in an aperture in the side of said supporting member to engage said holding device, wedging means for forcing said member outwardly, means for actuating said wedging means, and clamping means on said holding device actuated by said element for holding the drilling machine in position.

18. A supporting mechanism for drilling machines comprising the combination of a hollow cylindrical supporting member, a drilling machine, a holding device for the drilling machine on said supporting member, a securing element movable in an aperture in the side of said supporting member to engage said holding device, wedging means for forcing said member outwardly, fluid pressure means including a cylinder within said hollow supporting member for actuating said wedging means, and clamping means on said holding device actuated by said element for holding the drilling machine in position.

19. In a supporting mechanism for drilling machines the combination of an elongated supporting member having a plurality of outwardly movable segments distributed throughout its working length, means for supporting a drilling machine having an aperture for receiving said elongated supporting member and adapted to be clamped thereon at any desired position throughout the length of said member by the engagement of said segments with the walls of said aperture, and power-operated means within said elongated supporting member for moving said segments outwardly into clamping position.

20. A supporting mechanism for drilling machines comprising the combination of an elongated supporting member, a plurality of outward-

ly movable segments arranged in spaced relation throughout the length of said supporting member, means for actuating said segments, and a drilling machine support carried by said supporting member and adapted to be secured thereto by the outward movement of said segments, the

spacing of said segments being less than the width of said drilling machine support, so that the support can be secured to the elongated supporting member at any position throughout the length of said member.
